UNITED STATES PATENT OFFICE.

WILLIAM A. HOUCK, OF READING, PENNSYLVANIA.

COP-MOUNTING.

1,169,539.

Specification of Letters Patent. Patented Jan. 25, 1916.

Application filed February 4, 1915. Serial No. 5,996.

To all whom it may concern:

Be it known that I, WILLIAM A. HOUCK, a citizen of the United States, residing at Reading, in the county of Berks and State 5 of Pennsylvania, have invented certain new and useful Improvements in Cop-Mountings, of which the following is a specification.

My invention consists in an improved cop 10 mounting for knitting machines or the like, and the principal object in view is to provide for so controlling the unwinding thread as to effectively avoid any tangling or breakage such as is ordinarily liable to occur. It 15 is fully described in connection with the accompanying drawings, and the novel features are specifically pointed out in the claims.

Figure 1 is a sectional elevation of a device 20 embodying my complete invention in preferred form, the parts being illustrated in normal position preliminary to placing a full cop thereon. A partially used cop is indicated in dotted lines, together with the 25 corresponding position of the movable thread-supporting disk. Figs. 2, 3, and 4 are separate detail views.

The partially used cop 2, which is indicated in dotted lines, represents an ordinary 30 form wound upon an inner tube or quill 3; the latter ordinarily fitting upon a spindle or support perpendicularly fixed to a suitable bracket or base plate 5.

My invention consists in the novel mounting therefor, as fully described.

The quill 3, as shown, is of the usual conical form, and fits upon a correspondingly shaped sleeve 10, fixed to the supporting spindle 11. This spindle is adjustably fixed 40 to the base plate 5; its squared and screw-threaded lower end portion 12 extending through a square aperture in the base plate as illustrated, and being provided with a regulating nut 13 for lowering the spindle, 45 while a spring 14 is arranged to press it upward, thus enabling it to be conveniently and accurately adjusted perpendicularly.

A cylindrical cup 20 is provided on the base plate 5, concentric with the cop supporting spindle 11, and is formed with an outwardly flanged rim 21. Slidably mounted upon this cup is a dished thread-supporting disk 22, which is normally raised against said rim flange by a light coiled spring 23. 55 When a full cop 2 is placed tightly upon its support 10-11, the outer edge portion

thereof is adapted to bear upon the thread-supporting disk 22, and to press the latter downward from its normal position shown in the drawing; the purpose being to provide a support for any sagging of the thread as it is unwound from the cop and to prevent the thread from getting under the cop or tangling so as to interfere with proper operation. As the cop is reduced in diameter by the unwinding of its thread, the disk 22 is pressed upward upon the cup 20 by the spring 23 as required, so as to at all times lightly contact as stated with the edge of the gradually reducing cop.

The quills 3 of different cops, and the winding of the thread thereon relative to the lower edge 3^a thereof, ordinarily vary so as to call for perpendicular adjustment of the cop support as already described; the adjusting nut 13 being readily turned as may be required to so position the full cop that the disk 22 will be properly lowered at the start, and thus permit of its automatically following up as the cop is reduced in diameter by the unwinding.

It will be understood that the weight of the cop is at all times wholly carried by the support 10-11, and that the contact of the thread-supporting disk 22 with the outer 85 bottom edge thereof is effected merely by the light spring 23; so that such contact will produce no objectionable friction though adapted to satisfactorily serve the purpose described.

The specific construction shown may obviously be modified without departing from the essentials of the invention as defined in the claims.

What I claim is:

1. In combination with a supporting base, a thread supporting disk mounted thereon, a central cop support comprising a spindle having a screw-threaded end projecting through said base and a cop-engaging sleeve 100 fixed to the spindle above said base, a spring seating between said base and sleeve, and a nut to perpendicularly adjust said spindle upon said base.

2. In combination with a supporting base, 105 a cop support fixed thereto arranged to rigidly carry the cop, and a spring-pressed disk of dished form adapted to automatically maintain contact with the outer bottom edge of the cop.

3. In combination with a base plate, a cop support perpendicularly adjustable thereon,

and a concentric spring-pressed thread-supporting disk carried thereby.

4. In combination with a base plate, a flanged-rim cup thereon, a central cop support fixed thereto, and a spring-pressed thread-supporting disk slidable on said flanged cup.

5. In combination with a base plate, a flanged-rim cup thereon, a central cop support perpendicularly adjustable on said

plate and a spring-pressed thread-supporting disk slidable on said flanged cup.

In testimony whereof I affix my signature in presence of two witnesses.

WILLIAM A. HOUCK.

Witnesses:

D. M. STEWART,

HENRY B. HINTZ.
